UNITED STATES PATENT OFFICE

WILLIAM H. PETIT AND EDSON S. HINELINE, OF ROCHESTER, NEW YORK, ASSIGNEES
TO THE FOLMER GRAFLEX CORPORATION, OF ROCHESTER, NEW YORK, A COR-
PORATION OF NEW YORK

DESIGN FOR A COMBINED STUDIO CAMERA CASING AND SUPPORT THEREFOR

Application filed October 14, 1931. Serial No. 41,391. Term of patent 14 years.

To all whom it may concern:

Be it known that we, WILLIAM H. PETIT and EDSON S. HINELINE, citizens of the United States, residing at Rochester, county of Monroe, and State of New York, have invented a new, original, and ornamental Design for a Combined Studio Camera Casing and Support Therefor, of which the following is a specification, reference being had to the accompanying drawing, forming part thereof.

The figure of the drawing is a perspective view of a studio camera casing and support therefor showing our new design.

We claim:

The ornamental design for a combined studio camera casing and support therefor substantially as shown.

WILLIAM H. PETIT.
EDSON S. HINELINE.
